US00D591329S

(12) **United States Design Patent**
Wang

(10) **Patent No.:** **US D591,329 S**
(45) **Date of Patent:** **** Apr. 28, 2009**

(54) **EYEWEAR**

(75) Inventor: **Bao Lien Wang**, Tainan (TW)

(73) Assignee: **Wiley X, Inc.**, Livermore, CA (US)

(**) Term: **14 Years**

(21) Appl. No.: **29/293,695**

(22) Filed: **Dec. 7, 2007**
